CAN TESTING MACHINE

Carl F. Peck, Jersey City, N. J., assignor to American Can Company, New York, N. Y., a corporation of New Jersey

Application April 1, 1941, Serial No. 386,380

7 Claims. (Cl. 209—82)

The present invention relates to container or can testing machines and has particular reference to testing for interior collar bands utilized in certain kinds of cans.

In sheet metal cans used for coffee, vegetable shortening and many kinds of products, the opening of the can is usually effected by the removal of a tearing strip formed in the can body adjacent its top end. Removal of the tearing strip releases the entire top end of the can so that access to the can interior may be readily had. An interior collar band is provided in cans of this character adjacent the tearing strip to form a seat for the released top end of the can so that the latter may be replaced on the can and thus used as a reclosure cover. The collar band is sometimes made as a separate piece and is usually assembled with the can body and is beaded in place by automatic machinery.

Occasionally the collar band is inadvertently omitted from a can or is inserted incorrectly and such a can if run through the lines and filled as other cans, when opened will cause considerable trouble to the purchaser. The instant invention contemplates overcoming this difficulty by providing a testing device which detects cans in which the collar bands are not correctly in place and which discards these cans so that they will not be carried further through lines and will therefore be prevented from being used.

An object therefore of the invention is the provision of a collar can testing device which detects cans in which the interior collar bands have been omitted or have been incorrectly inserted and discards these cans from the line so that they will be prevented from being used when of such improper construction.

Numerous other objects and advantages of the invention will be apparent as it is better understood from the following description, which, taken in connection with the accompanying drawings, discloses a preferred embodiment thereof.

Referring to the drawings:

Figure 1 is a side elevation of a portion of a can testing machine embodying the instant invention, with parts broken away and parts shown in section;

Fig. 2 is a detail of one unit of the machine illustrated in Fig. 1 showing the movable parts of such a unit in a different position;

Fig. 3 is an enlarged combined elevation and sectional view of another portion of the machine illustrated in Fig. 1;

Fig. 4 is an enlarged perspective view of a portion of the machine, with parts broken away;

Fig. 5 is an enlarged sectional view taken substantially along the line 5—5 in Fig. 1, with parts broken away;

Fig. 6 is a side elevation of a part of the mechanism shown in Fig. 5 and viewed along a plane indicated by the broken line 6—6 in Fig. 5;

Fig. 7 is an enlarged sectional detail taken substantially along the line 7—7 in Fig. 1, with parts broken away;

Fig. 8 is a wiring diagram of the electrical apparatus used in the machine; and

Figs. 9, 10 and 11 are greatly enlarged sectional views of a portion of the machine showing the collar band end of a can in place, Fig. 9 illustrating the relative position of the machine parts and a can having a correctly inserted collar band, Fig. 10 illustrating the relative position of a can having a collar band incorrectly inserted, and Fig. 11 showing the relative position of a can in which the collar band has been entirely omitted.

As a preferred embodiment of the instant invention the drawings illustrate principal parts of a can testing machine of the character disclosed in United States Patent 2,019,517, issued November 5, 1935, to M. E. Widell. In such a machine sheet metal cans A having one end open are subjected to air under pressure and if found to leak are discharged from the machine by way of a leaky can outlet while good cans, i. e., cans which do not leak, are discharged from the machine by way of a good can outlet.

In the instant invention the cans A to be tested carry interior annular collar bands B (Fig. 9) which fit snugly within the can bodies in engagement with their side walls. The upper edge of the collar bands are bent inwardly and downwardly to provide a smooth curled edge C which extends inwardly from the collar band side wall. The lower edge of the collar band is preferably straight, i. e., with a raw edge and adjacent this edge the band normally is expanded outwardly into a bead D formed in the can body to hold the band in proper place. Usually such a body bead is formed at the same time the band edge is expanded.

The cans A roll on their sides into the machine in a continuous procession by way of an inclined runway 11 (Fig. 1). Adjacent the machine end of the runway a rotating star wheel 12 picks up individual cans and advances them in timed and spaced order along a pair of parallel guide rails 13. The guide rails direct an advancing can into horizontal alignment with a testing head unit generally indicated by the numeral 14.

There are a plurality of these testing head units

14 and they are carried on a pair of spaced and parallel rotating wheels 15, 16 (see also Fig. 4) mounted on a shaft 17 journaled in bearings formed in a machine main frame 18. The wheels are rotated in any suitable manner such as that disclosed in the above mentioned patent.

Each testing head unit 14 includes a stationary head 21 (Fig. 4) having a protruding short cylindrical mandrel 22 which is disposed eccentrically with the head 21 and a movable head or clamp pad 23 which is located adjacent the inner end of the mandrel. The stationary head is bolted to the wheel 16. The clamp pad is secured to an arm 25 which is keyed to and which slides on a cross shaft 26 having its ends carried in the wheels 15, 16. The arm is shifted on the shaft 15 in any suitable manner operating in time with the other moving parts of the machine.

When an entering can A is advanced into position to be received in a testing head unit 14, the clamp pad 23 of the unit is spaced away from the free end of the mandrel 22 and the can is brought into such a space and into position between the mandrel and the pad, with its open end adjacent the mandrel. The clamp pad then moves in against the closed end of the can and pushes the can longitudinally of its axis and onto the mandrel. This moving of the can into place and the positioning of it on the mandrel is done while the wheels 15, 16 are rotating and while the described parts are being carried around the axis of the shaft 17.

The mandrel 22 is somewhat smaller than the interior diameter of the can inside the curled edge of the collar band so that the can may be readily pushed onto the mandrel. However, the mandrel adjacent its base is provided with a small block or shoe 31 (see also Figs. 9, 10 and 11) having an inwardly inclined surface 32. The outer surface of the shoe is thus outside of the mandrel.

While a can A having a correctly inserted collar band B, as shown in Fig. 9, is being pushed onto the mandrel and before it is clamped in position against the head 21 by the clamp pad 23, the curled edge C of the collar band rides up on the shoe 31. The outer surface of the shoe projects beyond the mandrel surface a distance sufficient to shift the can laterally of the mandrel into a position concentric with the head 21. This action effects a snug fit of the can on the mandrel. After the can is thus centered on the head 21 the clamp pad holds it tightly in this position.

If the collar band B is in a reverse position in its can A its curled edge C is not in a correct position. This is shown in Fig. 10 and it will be observed that the curled edge C does not ride up on the shoe 31 and hence the can is not centered on the head 21. This off-center or eccentric position of the can with its incorrectly placed collar is utilized to effect the discard of the can in a manner which will be hereinafter explained.

In a similar manner a can A which has no collar band at all, as shown in Fig. 11, also remains in an eccentric position relative to the testing head 21 and such a can is also discarded from the machine. Thus far in this description the cans have just been placed on the mandrel. Their collar band condition has not been determined.

All cans after being clamped in place on the testing heads 21 are carried around through a curved path of travel with the wheels 15, 16 as they rotate on the axis of the shaft 17. It is during this travel of the cans that they are tested for their collar band condition. This testing for

the collar bands is brought about by a detecting device which includes a detector arm 35 (Figs. 1 and 4) which extends into the path of travel of the clamped cans.

The detector arm 35 is mounted on a cross shaft 36 carried in a bearing 37 secured to the main frame 18 and in a bearing 38 fastened to a bracket 39 which is bolted to the frame. The shaft carries a lever arm 42 which is retained under tension of a spring 43, this spring having one end hooked into the arm and having its opposite end attached to a pin 44 secured in the machine frame. The outer end of the lever arm carries an adjustable setscrew 46 which is in alignment with a movable element 47 of a normally open electric switch 48.

The tension spring 43 keeps the detector arm 35 in the path of the outside surfaces of the cans A moving past with the rotating wheels 15, 16. The cans in the wheels are spaced close together and the detector arm is sufficiently long so that when a procession of good cans, concentrically located on the testing heads 14 by the properly located collar bands within them, pass by the detector arm, the latter is maintained in a practically stationary condition.

However, when a bad can which is eccentrically located on its testing head because of a lack of collar band or an incorrectly located collar band, approaches the detector arm 35, the outer surface of the wall of the bad can does not extend out as far as the good cans and hence the detector arm is allowed to move inwardly to engage it as it passes. This movement of the detector arm allows the cross shaft 36 and the lever arm 42 carried thereon to rock as the spring 43 contracts and this closes the electric switch 48. Closing of the switch sets in motion a time delay mechanism generally indicated by the numeral 51 (Fig. 1) and this mechanism controls the discharge of the bad can at the proper time by way of a discharge device 52.

The time delay mechanism 51 includes a normally yieldable lever cam 55 (Figs. 5 and 6) which is mounted on a pivot pin 56 carried in lugs 57 formed on a depending bracket 58 secured to a frame extension 59 of the main frame 18. The lever cam is disposed at an angle to the bracket so that it extends substantially parallel to the periphery of the wheel 15. A compression spring 50 62 is interposed between the lever cam and the bracket to force the free end of the cam inwardly toward the wheel. A lug 63 formed on the lower end of the lever cam carries an adjustable setscrew 64 which is set to limit the inward travel of the cam.

In its normal inner position, the lever cam 55 is in the path of travel of a plurality of delay buttons 67 (Figs. 1, 4, 5 and 7) which are carried in the wheel 15. There is one of these buttons 60 for each testing head unit 14. The buttons are formed on the outer ends of long stems 68 which slide in bores 69 in the outer ends of the cross shafts 26. The stems are prevented from rotating by a setscrew 71 which is threaded into a groove 72 in the shaft and which extends into a groove 75 in the stem.

When good cans are passing over the detector arm 35, the delay buttons 67 engaging against the lever cam 55 as they pass, push the latter outwardly. The pivotal mounting of the lever cam and the compression spring 62 permit of this movement of the cam. However, when a bad can is engaged by the detector arm 35 the lever cam 55 is locked against movement and the button 67

corresponding to this bad can is itself pushed inwardly toward the wheel. This will be further described.

The locking of the lever cam is preferably brought about by a vertically disposed locking pawl 75 (Figs. 5 and 6) which is mounted on a pivot pin 76 carried in the bracket 58. The upper end of the pawl is located adjacent a locking lug 77 formed on the outer surface of the lever cam 55 and adjacent a locking lug 78 disposed on the inner surface of the bracket 58. The upper end of the pawl is maintained under pressure of a flat spring 81 which engages against the free end of the pawl and which is secured to a block 82 formed on the bracket 58. The pawl adjacent its pivot pin 76 is connected with a movable core element 85 of a normally energized electric solenoid 86 connecting with the detector switch 48.

The energized solenoid 86 normally keeps the locking pawl 75 away from the locking lugs 77, 78 holding it from between the lugs and against the pressure of the flat spring 81. When the pawl is in this normal position the lever cam 55 is free to move.

When a bad can is detected and the electric switch 48 is closed as a result of its detection as already mentioned, the solenoid 86 is immediately deenergized and the flat spring 81 thereupon forces the pawl into a position interposed between the locking lugs 77, 78. The pawl is of sufficient thickness to occupy the normal space between the lugs and thereby prevents the lever cam from moving back. The lever cam is thus locked against movement and it is this locking that pushes in the delay button 67 as hereinbefore mentioned. This pushed-in delay button is utilized to discharge the bad can into the proper outlet of the discharge device 52 when the can reaches this latter device, as will now be explained.

The discharge device 52 is located adjacent the can entrance runway 11 and is preferably of the character disclosed in the above mentioned Widell patent. Such a discharge device includes a casing 91 which encloses an upper or good can outlet or runway 92 and a lower or bad can outlet or runway 93. The good can outlet may empty into a continuing chute or runway to carry the good cans to any suitable place of deposit while the bad can outlet may empty into a basket or other container adapted to receive the bad cans.

Adjacent the entrance end of the discharge device 52, there is a movable gate 95 mounted on a pivot shaft 96 carried in bearings formed in the casing 91. This gate is adapted to be raised and lowered in accordance with the detection of good and bad cans to direct them into the proper discharge outlet. When good cans are detected the gate is rocked into the position shown in Fig. 2 and the gate thus forms a part of the floor of the upper runway. When bad cans are detected the gate is raised as shown in Fig. 1 to block off the upper runway and to direct the bad can into the lower runway. A star wheel 97 mounted on a continuously rotating shaft 98 journaled in bearings formed in the casing 91 receives the cans from the testing head units 14 and delivers them into the discharge device.

The normal position of the gate 95 is shown in Fig. 2 which is the position for good cans since the greater number of cans passing through the discharge device is of this character. Hence the gate is only occasionally rocked into its raised position as when a bad can is detected. This

rocking of the gate is brought about by a pushed-in delay button 67.

When such a pushed-in button 67 comes adjacent the discharge device it engages against and rocks a bell crank lever 101 (Fig. 1) mounted on a pivot pin 102 carried in the frame extension 59. The bell crank lever is connected by a link 104 (see also Figs. 5 and 6) to a lever 105 mounted on a short shaft 106 carried in a bearing 107 formed in the bracket 58. Beyond the bearing the shaft carries a switch arm 108 of a normally closed contact switch 109.

Hence when a pushed-in button 67 rocks the bell crank 101, the link 104, lever 105, shaft 106, and contact arm 108 are also rocked and this opens the switch 109. Normally positioned buttons for good cans escape the bell crank 101 as they pass by and hence the switch remains closed for these good cans.

The contact switch 109 controls the operation of a normally energized solenoid 112 (Fig. 3) and the opening of the switch de-energizes the solenoid. The solenoid in turn controls the operation of the gate 95 in the discharge device 52 in the manner disclosed in the above mentioned Widell patent. Briefly, this mechanism includes a depending gate arm 113 which is loosely mounted on an outer end of the gate shaft 96 and which is connected to a continuously reciprocating stroke bar 114 operated in a suitable manner, as in the Widell patent. The stroke bar makes one stroke for every can A as it approaches the discharge device.

Adjacent the gate arm 113 the gate shaft 96 carries a latch arm 116 which is fixed on the shaft and which is disposed in an upright position. The arm carries a short pivot shaft 117 on one end at which is mounted a pawl 118. The pawl hangs down adjacent a tooth 119 formed on the hub of the gate arm 113. The pawl is maintained under control of a tension spring 121 having one end connected to the pawl and its opposite end secured to the latch arm.

The pivot shaft 117 also carries a depending actuating arm 124 which terminates adjacent the outer end of the gate shaft 96 and which carries a pin 125 located substantially in alignment with the axis of the gate shaft. The pin operates in a slot 126 formed in a horizontal link 127 pivotally connected to a movable core 128 in the electric solenoid 112.

Hence as long as the solenoid 112 is maintained energized, as when good cans are passing through the machine, the core 128 holds the link 127 in a position in which the pin 125 of the actuating arm 124 is in an off-center relation to the axis of the gate shaft 96 as shown in Fig. 3. In this position of the pin 125 the pawl 118 is held away from the tooth 119 on the gate arm 113. Hence as the gate arm swings back and forth with the reciprocating stroke bar 114, the arm rocks on the gate shaft while the shaft and the gate 95 secured thereto remains idle in the position shown in Fig. 2.

When the solenoid 112 is de-energized by the detection of a bad can, the core 128 moves outwardly under the resistance of a compression spring 131 housed in the solenoid. This shifts the link 127 toward the left as viewed in Fig. 3 and hence the pawl spring 121 rocks the actuating arm and also rocks the pawl 118 into engagement with the hub of the gate arm 113. Thus on the next stroke of the stroke bar 114 the tooth 119 on the gate arm engages against the pawl and this rocks the gate arm and the latch arm 116

as a unit. Rocking of the latch arm rotates the gate shaft 88 and thus raises the gate 85 into the position shown in Fig. 1 to permit the bad can to be discharged into the lower runway 93 of the discharge device 52, as hereinbefore explained. The solenoid is immediately re-energized after the discharge of the bad can so that it will be in readiness for the next following can in the tester wheels.

As the empty testing head unit 14 from which a can A has just been discharged approaches the new can entrance runway, the delay button 67 is re-set in case this pin has been pushed in as for a bad can as just explained. This re-setting is preferably effected by a stationary cam block 138 (Figs. 1 and 7). The cam block is located adjacent the path of travel of the buttons 67 and is carried on a bracket 136 which is bolted to the frame extension 59. One side of the cam block is formed with a tapered cam surface 138 and this surface is engaged by the pushed-in buttons as they move past the block. The tapered cam surface draws the buttons outwardly into their original position in readiness for the next detecting operation. This completes the collar band testing cycle of the machine.

The electric connections in the detecting device will now be explained and reference should be had to the wiring diagram in Fig. 8. In this diagram the various switches and solenoids are interconnected in a plurality of electric circuits which include a detector circuit X, a delay circuit Y, and a discharge circuit Z. These circuits transmit electric energy from any suitable source of power such as a generator 141 which is provided with a main outlet wire 142 and a return wire 143.

The detector circuit X includes the switch 48 which is first closed by the detection of a bad can as hereinbefore explained. One terminal of this switch is connected by a wire 145 to the generator outlet wire 142. The other terminal is connected by a wire 146 to a solenoid 147 of a normally closed relay switch 148. The solenoid is also connected by a wire 149 to the generator return wire 143.

Hence when the normally open detector switch 48 is closed electric energy flows through the detector circuit and thus energizes the relay solenoid 147. This opens the relay switch 148.

The relay switch 148 forms a part of the delay circuit Y which also includes the normally energized delay solenoid 86. In this circuit one end of the delay solenoid 86 is connected by a wire 152 to the generator outlet wire 142 while the other end of the solenoid is connected by a wire 153 to the relay switch 148. This switch is also connected by a wire 154 to the generator return wire 143.

Hence when the relay switch 148 opens, the delay circuit is broken and the normally energized delay solenoid 86 becomes de-energized. It will be recalled that the de-energization of this solenoid locks the lever cam 55 and thereby pushes in a delay button 67 to mark a bad can.

The discharge circuit Z includes the normally closed switch 100 and the normally energized solenoid 112. The switch is connected by a wire 156 to the generator outlet wire 142 and by a wire 157 to the solenoid. The solenoid is also connected by a wire 158 to the generator return wire 143.

Hence electric energy from the generator 141 normally flows through this circuit, but when the switch 100 is opened by a pushed-in delay

button 67, as hereinbefore explained, the circuit is broken and the solenoid 112 becomes de-energized. It is this de-energizing of the solenoid that opens the discharge gate 85 and thus directs the released bad can into the bad can runway of the discharge device 52.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. In a machine for testing containers for internal collar bands, the combination of a support head, a mandrel eccentrically disposed on said head for supporting a container to be tested, a tapered shoe on said mandrel and engageable with a properly fitted collar band in a container positioned on the mandrel for holding said container in a position concentric with said head, and detecting means engageable with the outside of a container on said support for detecting eccentrically positioned containers as containers having improperly fitted collar bands and containers having no collar bands at all.

2. In a machine for testing containers for internal collar bands, the combination of a rotatable wheel, a plurality of spaced supports on said wheel for conveying containers to be tested along a predetermined curved path of travel, means on said supports for holding containers with properly fitted collar bands in a position different from that of containers with improperly fitted collar bands, a detector arm pivotally mounted adjacent the path of travel of the containers and engageable with the outside of the containers as they move past it, said arm being movable by a container having an improperly fitted collar band, discharge devices for separating the detected containers from the others, and electric instrumentalities operable by said detector arm for actuating said discharge devices.

3. In a machine for testing containers for internal collar bands, the combination of a rotatable wheel, a plurality of spaced supports on said wheel for conveying containers to be tested along a predetermined curved path of travel, means on said supports for holding containers with properly fitted collar bands in a position different from that of containers with improperly fitted collar bands, a detector arm pivotally mounted adjacent the path of travel of the containers and engageable with the outside of the containers as they move past it, said arm being movable by a container having an improperly fitted collar band, discharge devices for separating the detected containers from the others and for directing them to a place of deposit, time delay mechanism for actuating said discharge devices when the detected container comes adjacent them, and instrumentalities operable by said detector arm for setting said time delay mechanism.

4. In a machine for testing containers for internal collar bands, the combination of a rotatable wheel, a plurality of spaced supports on said wheel for conveying containers to be tested along a predetermined curved path of travel, means on said supports for holding containers with properly fitted collar bands in a position different from that of containers with improperly fitted

collar bands, a detector arm pivotally mounted adjacent the path of travel of the containers and engageable with the outside of the containers as they move past it, said arm being movable by a container having an improperly fitted collar band, discharge devices for separating the detected containers from the others and for directing them to a place of deposit, electric means for actuating said discharge devices, a movable delay button carried in said wheel adjacent said container support for operating said electric means when a detected container comes adjacent said discharge devices, instrumentalities operable by said detector arm for setting said delay button when a container having an improperly fitted collar band is detected, and means for resetting said delay button into its original position after a detected container has been discharged.

5. In a machine for testing containers for internal collar bands, the combination of a support for said containers, means on said support for engaging and holding a container to be tested, means cooperating with said holding means and engageable with a container to be tested to shift laterally relative to said support a container having a properly fitted collar band, and means engageable against the exterior side wall of a supported container for detecting containers having improperly fitted collar bands in accordance with the relative position of said containers laterally of said support.

10 5 15 20 25 30

6. In a machine for testing containers for internal collar bands, the combination of a support for said containers, means on said support for internally engaging and holding a container to be tested, means carried by said holding means and engageable with a container to be tested to shift laterally relative to said support a container having a properly fitted collar band, means engageable against the exterior side wall of a supported container for detecting containers having improperly fitted collar bands in accordance with the relative position of such containers laterally of said support, and discharge devices operable by said detecting means for separating the detected containers from the remaining laterally shifted containers and for discharging the former from the machine.

7. In a machine for testing containers for internal collar bands, the combination of a support for said containers, means on said support for engaging and holding a container to be tested, means cooperating with said holding means and engageable with a container to be tested to shift laterally relative to said support a container having a collar band in one position therein, and means engageable against the exterior side wall of a supported container for detecting containers having collar bands in another position therein.

CARL F. PECK.
